UNITED STATES PATENT OFFICE.

CHARLES H. SMITH, OF BOSTON, MASSACHUSETTS.

DESIGN FOR AN IRONING-BOARD.

SPECIFICATION forming part of Design No. 31,756, dated October 31, 1899.

Application filed August 7, 1899. Serial No. 726,476. Term of patent 14 years.

To all whom it may concern:

Be it known that I, CHARLES H. SMITH, of Boston, in the county of Suffolk and State of Massachusetts, have invented and produced 5 a certain new and original Design for an Ironing-Board, of which the following is a specification, reference being had to the accompanying drawing, forming a part thereof.

This invention relates to a new and original design for ironing-boards; and it consists in the novel features of shape and configuration hereinafter fully described and particularly claimed, and clearly illustrated in the drawing.

15 The drawing shows a perspective view of my design.

1 represents a flat-surfaced ironing-board having in top plan view an outline curved at each end, the curve at one end being of a 20 much longer radius than the curve at the other end, the curves of the smaller end be-

ing connected with the curves of the larger end by inward curves.

The leading feature of my design consists of a flat-surfaced ironing-board having substantially vertical edges and having one end 25 larger than the other, one side of the larger end conforming approximately to one side and the two ends of an oval, the smaller end conforming approximately to one end and 30 parts of the two sides of another oval, the sides of the smaller end connecting with the larger end by inward curves.

I claim—

The design for an ironing-board substantially as shown and described.

In testimony whereof I have affixed my signature in presence of two witnesses.

CHARLES H. SMITH.

Witnesses:

E. BATCHELDER,
P. W. PEZZETTI.
